UNITED STATES PATENT OFFICE.

LESLIE H. BURLIN, OF CHICAGO, ILLINOIS.

WOOD-TURNING MACHINE.

Application filed October 20, 1921. Serial No. 509,173.

To all whom it may concern:

Be it known that I, LESLIE H. BURLIN, a citizen of the United States, residing at Chicago, in the county of Cook and State of Illinois, have invented new and useful Improvements in Wood-Turning Machines, of which the following is a full, clear, and exact description of the abandoned application filed January 8, 1920, Serial No. 350,123, for which this application is substituted.

Heretofore wood turning has been accomplished mostly by means of chisels held in the hands of the operator or by machines in which the chisels were clamped in suitable devices or in which rotary cutters that were employed were moved laterally into contact with the rotating work. When done by hand wood turning is a very slow and expensive job, and when done by machine it requires considerable time to adjust the machine to do the work and the machine has to be stopped on an average of every five hours in order to sharpen the chisels or cutters. In addition to these objections wood turning machines are very expensive and must be operated by expensive expert labor.

The object of my invention is to provide a comparatively simple and cheaply constructed wood turning machine the cost of which is within the means of any machine shop, which can be operated by inexperienced and cheap labor, which can be adjusted within fifteen minutes to cut any turned design, in which the rotary cutting devices will last on an average of three times as long as the wood turning machines heretofore in use, and which does its work more quickly and smoothly than the machines heretofore in use. This I accomplish by the means hereinafter fully described, and as particularly pointed out in the claims.

In the drawings:

Figure 1 is a side elevation of my invention.

Figure 2 is a plan view of the same.

Figure 3 is a detail view showing a section taken on line 3—3, Figure 2.

Figure 4 is a transverse section taken on line 4, 4, Figure 1.

Figures 5, 6, and 7, are diagrammatical views illustrating my invention.

In the drawings 5 represents a suitable table or bench; 6 and 7 represent two standards the bases of which are secured to the top of said bench near the rear longitudinal edge of the same. The upper end of stand-

ard 6 is provided with a bearing for a longitudinal spindle 8, and this spindle has a pulley on its left hand end, which is driven through the medium of a belt 9 by an electric motor 10.

The right hand end of said spindle extends through its bearings and has an arbor 11 mounted thereon which has a couple of spurs (not shown) projecting therefrom, that project into the end of the bar or blank of wood and assist in retaining it in axial alinement with the arbor. The upper end of the standard 7 has a boss 12 that is tapped axially by a centering screw 13 the axis of which alines with the axis of the arbor.

Mounted on the top of the bench in line with the bases of the standards are two goose-necks, 14, 14, the upper portions of which curve to the rear and the upper ends of which are connected by single rail 15. Suspended from this rail by means of hangers 16, 16, is a platform 17, the upper ends of said hangers being looped around the rail and having concaved wheels 18, 18, 80 that travel back and forth on the same.

The platform 17 is of such width that there is a clearance between the same and the rear edge of the bench, and mounted on an inclined dais 21 on this platform is an electric motor 19. The left hand end of the armature shaft 22 extends beyond the casing thereof and has a circular saw 20 secured thereto. As the axis of the armature shaft is parallel with the inclined surface of the dais the plane of the periphery of the saw is inclined to the left from its uppermost segment or top towards its lowermost segment, thus when the saw is moved towards and cuts into the work it eats into and removes the left hand wall of its kerf as the platform is moved from right to left. This saw is several times the diameter of the work so that only a small proportion of its periphery is engaged with the work at any one instance, and the heating and the wear is lessened by being distributed over a great number of teeth, only a small portion of which enter the work at the same time. It is this relative size of the saw, and its relative thinness with reference to its diameter, which lends a special importance to the inclination in two planes of the saw to the work, facilitating the travel of the saw and lessening its tendency to bury itself in the work so as to make difficult its movement longitudinally of the work.

100

105

110

When the saw is not revolving its perimeter is not in contact with the work. It is moved toward and away from the axis of the work to increase or decrease the depth 5 of its kerf by means of a lateral arm 23, one end of which is suitably secured to the platform, and the other end of which extends over the bench and has its extremity turned downwards to form a finger 24 which is 10 adapted to enter the groove 25 in the plate or pattern 26. This pattern 26 is preferably screwed or otherwise removably secured to the top of the bench next the front edge of the latter and, the groove is disposed in a 15 longitudinal direction in the pattern and its course follows the lines or sinuous courses of the exterior of the turning it is desired to cut from one end of the work to the other.

The arm 23 is preferably provided with a 20 vertical handle 27 that arises from near its forward extremity. The operator grasps this handle and moves the platform and the saw carried thereby from right to left, and the finger in the groove moves the saw towards and away from the axis of the work 25 as it travels lengthwise in the same.

If desired, instead of the operator depending upon the handle 27 to feed the saw to the work, a chain or cable 30 could be 30 secured to the left hand edge of platform 17 and extend to and around a drum 31 mounted on a transverse shaft 32 journaled in bearings 33 at the left hand end of the bench, and a crank 34 or handwheel be secured to the front end of this shaft to turn it as fast or as slow as it was desired to have the saw move.

I prefer to rotate the saw and the work in the same direction so that the movement of 40 the contacting surfaces of the perimeters of the saw and work will be opposed to one another.

By inclining the saw in the manner hereinbefore described and as illustrated in the 45 drawings, the side of the kerf is cut away from right to left. While I prefer to incline the saw, yet it is possible to so mount the same at right angles to the axis of the work, and to so cut the teeth that the periphery described by the same, that is its cutting edge, will be oblique to the axis of the work.

Figures 6 and 7 illustrate embodiments of the idea of means of the preceding paragraph. The essential idea embodied in each 55 of these figures is that of having the cutting face of the saw disposed at an angle to the axis of the work. One way of accomplishing this end is by disposing the saw and its shaft in such a manner that the horizontal section 60 shows the saw disposed at an angle to the face or to the axis of the work. This is shown in Figure 6. Under this embodiment the shaft of the saw in addition to being inclined to the horizontal as shown in Figure 65 1 of the drawings, is also inclined to the

axis of the work in the horizontal plane. Another way of accomplishing the same end of having the cutting face at an angle to the face or the axis of the work is as shown in Figure 7, to have the cutting edge of the saw on a bevel with relation to the faces of the saw. In this construction the shaft of the saw would be inclined only in the vertical plane and not in the horizontal plane. 70

It will, of course, be realized that instead of the saw being carried longitudinally parallel to the axis of the work, said work may be moved longitudinally and fed to the saw which latter would revolve in a fixed 75 plane. 80

What I claim as new is:

1. A wood turning machine comprising a bed, work spindles disposed on said bed, a curved support disposed at each end of the bed and having their upper ends connected with a rail, a platform suspended from said rail, movably along said rail and oscillating transversely of said rail, said platform having mounted thereon a wood cutting saw whose diameter greatly exceeds that of the work and means for rotating said saw, the axis of the said saw being inclined to the horizontal and the cutting edge of the saw being inclined to the axis of the work, an arm projecting from said platform having a downwardly projecting lug, means disposed on the bed cooperating with said lug for guiding the cutter longitudinally and transversely. 90

2. A wood turning machine comprising a bed, work spindles, a circular wood cutting saw whose diameter greatly exceeds that of the work, means for suspending the saw to permit longitudinal and transverse movement thereof, the saw being so disposed that the plane of rotation of the saw is inclined to the vertical and its cutting edge is inclined to the axis of the work in a horizontal plane. 100

105

3. A wood turning machine comprising a bed, work spindles, a platform having a circular wood cutting saw whose diameter greatly exceeds that of the work and means for rotating same mounted thereon, means

110

for suspending the platform to permit longitudinal and transverse movement thereof,

the saw being so disposed that the plane of rotation of the saw is inclined to the vertical and its cutting edge is inclined to the axis of the work in a horizontal plane, and means disposed on the bed and on the platform to guide the movement of said platform. 115

120

4. A wood turning machine comprising a bed, work spindles, a circular wood cutting saw, whose diameter greatly exceeds that of the work, means for suspending the saw to

125

permit of longitudinal and transverse movement thereof, the saw being so disposed that the plane of rotation of the saw is inclined to the vertical and its cutting edge is in-

130

clined to the axis of the work in a horizontal plane, means for guiding the longitudinal and transverse movement of the saw in conformance with the desired shape of the work, and manually operable means for moving the saw longitudinally of the bed.

5 In witness whereof I have hereunto set

my hand and seal this seventh day of October 1921.

LESLIE H. BURLIN.
